UNITED STATES PATENT OFFICE.

HERMAN MILLER, OF OAK PARK, ILLINOIS, ASSIGNOR OF ONE-THIRD TO CHARLES G. NOVAK AND ONE-THIRD TO ORIN H. GLOVER.

OIL BURNER FOR HEATING FURNACES AND THE LIKE.

Application filed November 2, 1925, Serial No. 66,144.

To all whom it may concern:

Be it known that I, HERMAN MILLER, a citizen of the United States, residing at Oak Park, in the county of Cook and the State of Illinois, have invented certain new and useful Improvements in Oil Burners for Heating Furnaces and the like, of which the following is a specification, reference being had to the accompanying drawings, forming a part thereof.

The purpose of this invention is to provide an improved construction of a fuel mixer and burner for a heating furnace and the like employing vaporizable liquid fuel. It consists in the elements and features of construction shown and described as indicated in the claims.

In the drawings:—

Figure 1 is a vertical section of a furnace fire box equipped with a fuel mixer and burner embodying this invention.

Figure 2 is a top plan of the mixer and burner.

Figure 3 is a top plan view of the fuel distributer and breaker on a larger scale than the preceding figures.

In the drawings the furnace fire box wall is seen at 10, and the grate at 11. The mixer and burner of the furnace embodying this invention, indicated as to its entirety by the reference letter A, is adapted to be introduced into the fire box and supported on the grate, 11, in any convenient manner, as by fire brick support indicated at 12; and in order to be able to control the air supply so that all the air that enters the fire box of the furnace shall pass through the mixer and burner for effecting perfect combustion and avoiding cooling the resulting flame, the space around the burner and mixer device as it stands supported on the grate is desirably filled with fire brick or other suitable material as seen at 15 for substantially closing off the said space against passage of air into the fire box or subsequent draft passages of the furnace.

The mixer and burner comprises a supporting member, 20, which may be cast iron and comprises a peripheral foot element, 20^a, adapted to rest upon the fire brick support, 12, and a horizontal web, 20^b, having a central circular depressed area forming a basin, 20^c, apertured at the center of the bottom as seen at 20^d, the aperture being marginally flanged upwardly at 20^e, forming an annular

trough, 20^f, for a purpose hereinafter explained. At a plurality of positions, preferably symmetrically distributed around the central basin, 20^c,—as shown, at two positions only, 20^g, 20^g,—the web, 20^b, is apertured for the connection of air supply ducts, 21^a, which are preferably formed in a unitary casting, 21, said ducts leading upwardly from their connections at the apertures, 20^g, and extending in the fire box cavity to 60 any desired height and then reflexed downward and toward each other, meeting for a common discharge downwardly at 21^c, directly above the central aperture, 20^d, of the support, 20. Through the central aperture, 20^d, there is extended the fuel supply pipe terminal, 23, which leads by suitable pipe connections, 33, controlled by the valve, 24, from a suitably located fuel source (not shown) which, either by the head due to its 70 elevation above the level of the mixer and burner, or by the otherwise provided pressure, supplies the fuel in an upwardly discharging jet at a nozzle which terminates the pipe, 23, as will be hereinafter described. 75 22 is a fuel distributer and breaker, so-called because of its two functions, first, that of affording extended surface over which the liquid fuel which is discharged through the aperture of the terminal, 22^a, formed at the 80 center an apex of the conical distributer, flows for exposure to the air current which is directed downwardly onto said distributer from the air ducts above described, and secondly, that of presenting abruptly faced corrugations, 22^b, forming annular grooves or troughs, 22^c, in the upper conical face of the distributer, in which troughs the liquid fuel may accumulate to some extent before being evaporated, and wherein it is exposed to the 85 air blast directed upon it from the apex, 20^e, with the effect of insisting in breaking up the liquid fuel into a fine spray, or atomizing, for most completely effective exposure to the vaporizing action of the hot 90 air currents directed upon it. For it will be understood that when the device is in continuous normal operation, the fuel having been ignited as hereinafter described, the fire box above the burner is filled with flame, 95 causing the ducts, 20^a, to be highly heated, even to redness, so that the air current directed down upon the distributor and breaker, 20, is a hot blast capable of quickly 100 vaporizing the fuel which its impact tends 105 110

first to atomize as described. The fuel distributing and spreading device may be considered as comprising, in addition to the conical corrugated or grooved part, a disk, 25, which is mounted slidably on the fuel pipe terminal, 23, below said corrugated member, and is adjustable up and down on the pipe terminal, 23, in any convenient manner, as by means of supporting and adjusting screws, 26, set up through the bottom of the basin and carrying the disk, 25, on their upper ends. This disk, 25, in a small measure constitutes a part of the distributing device because its diameter is such that a marginal area of it is exposed upwardly outside of the periphery of the part, 20, so that the liquid fuel may drip onto it and be thus exposed to the air blast for vaporization. But its primary function is as a valve or damper to regulate the air gap above the marginal flange, 20^e, which forms a trough, 20^f, and also between the circumference of said damper and the outer slope, 20^c, of the basin.

It may be understood that in operating this burner the fuel will be first admitted to a limited extent by opening the valve, 24, to permit the fuel to be discharged with limited force through the nozzle, 22^a, and fall upon and flow over the distributor accumulating to some extent in the corrugation grooves thereof; and the valve, 24, being then closed, a lighting torch or the like will be used to light the oil thus accumulated, whereupon the valve, 24, may be again opened, and the oil discharged in a jet from the nozzle will be lighted and thereby the device will be in operation.

It will also be understood that the furnace draft operating of course more powerfully when the furnace becomes well heated causes inflow of air through the central aperture, 20^d, and out around the margin of the disk damper, 25; and also that a main quantity of air for supporting combustion is drawn in as above indicated through the ducts, 21^a, and deflected back for operating as an air blast meeting and driving back onto the distributor the liquid fuel discharged through the nozzle, A; and that the resulting fuel mixture ignited and burning is again reflexed upward, passing between the ducts, 21^a, 21^b, at both sides of the burner into and through the fire box to the flue passages of the furnace. The service and importance of the disk damper mounted adjustably as shown consists in that it is very important to control the distribution of air as between the central aperture, 20^d, and the ducts, 21^a, suitably according to the intensity of the draft afforded by the furnace, and its chimney connections. If the draft is not strong, it is desirable to adjust the disk damper for a relatively large air gap between its margin and the margin of the

flange, 20^e, of the trough, 20^f, and between the periphery of said disk damper and the outer slope of the basin, 20^c; and with such adjustment allowing a considerably large fraction of the total air admitted to pass through this air gap and the correspondingly limited amount to pass through the ducts, 21^a, the force of the air blast delivered through the ducts for dispersing and atomizing the liquid fuel, will be correspondingly low. But when the construction of the furnace or chimney with which it is connected is such as to afford a strong draft, the disk damper will be adjusted for reducing the air gap around it, with the effect of correspondingly increasing the proportion of air delivered through the ducts, 21^a, and the force of the air blast thus delivered for dispersing and atomizing the oil. This adjustment of the disk damper it will be understood, will be made at the time of setting up the burner in the furnace and in accordance with the ascertained normal draft of the furnace and chimney.

It may be understood that the trough 20^f is provided for receiving any excess of oil which may overflow from the groove 22^c, failing to be vaporized in the course of flow over the distributor; and this trough is therefore provided with a drain pipe 27 which leads outside the furnace to any conveniently-located receptacle not shown. It is of importance that this drain pipe leads out of the trough at or near the bottom thereof so that no accumulation of oil can occur therein to a height at which it would narrow the draft gap determined by the adjustment of the damper disk 25.

It is desirable, however, that the drain pipe should protrude up into the trough, 20^f, a sufficient distance to produce a shallow trap at the bottom of the trough wherein the excess fuel delivered through the nozzle may accumulate with considerable surface area exposed to the incoming cold air for cooling it before it overflows into the drain pipe, since obviously it is not desirable that it should pass hot into this drain pipe, so that it should be delivered to the drain receptacle in condition for vaporizing at normal atmospheric temperature. And for these two purposes, first, that the fuel may not accumulate in the trough so as to choke the draft, and second, that it may accumulate sufficiently to permit the accumulation to become cool before passing into the drain pipe, the pipe, 27, is shown protruding slightly above the bottom of the trough.

It will further be noted that the pipe, 23, which forms the inlet stem of the distributor, 22, is of greater inner diameter than the supply pipe, 23, and considerably greater than the aperture of the nozzle, 22^a. The purpose of this feature of the construction is to cause the cavity of the pipe stem, 22,

to serve as a chamber in which fuel may accumulate exposed to heat conducted from the distributor, 22, which, in the operation of the burner, becomes very highly heated and commonly at red heat, so that the oil is to some extent vaporized at this discharge from the nozzle, and is thereby in condition for being promptly and fully vaporized upon being driven back by air blast onto the hot surface of the distributor.

I claim:

1. A fuel mixer and burner for a heating furnace and the like comprising a support adapted to be mounted in the fire box of the furnace to be served and to be therein supplemented by means for completing the closure of the draft passages of the furnace except as to the openings through said support, said support having an air inlet aperture; a fuel supply pipe extending up through said aperture; a fuel distributor at the upper end of said fuel supply pipe apertured in alignment with the latter for discharge of fuel therethrough and thereabove; an air pipe connected for exterior air supply extending in exposure to the heat of the furnace and terminating for discharge downwardly upon said distributor for dispersing the fuel over the latter and vaporizing the same; a choke damper mounted for up and down movement on the fuel supply pipe above the air inlet aperture of the support, and means for adjusting said damper to vary the air access through said aperture.
2. A fuel mixer and burner for heating furnace and the like, comprising an oil distributor of general conical form apertured for oil discharge through its apex for flow back over the conical surface, and means for directing an air draught downward upon said distributor; an annular basin having an upwardly turning flange at its inner circumference forming an annular trough around the central aperture, the conical distributor being diametered at its base for overhanging said aperture and having its margin overhanging said trough; the marginal portions of said distributor being adjustable up and down relative to the upper conical surface of said distributor and to the basin, for varying the air gap between said marginal portion and said trough forming flange.
3. A fuel mixer and burner for heating furnace and the like, comprising a support adapted to be mounted in the fire box of the furnace to be served, and having a depressed area forming a basin and an air inlet aperture therethrough; a fuel supply pipe extending up through said aperture; a fuel distributor at the upper end of said pipe apertured in alignment therewith for discharge of fuel upwardly through said distributor, the support having another aperture and an air pipe connected thereto

above the support and extending thereabove in the fire box chamber, being reflexed therein for discharge downwardly toward the distributor, the depression in the upper side of the support being substantially frusto-conical in form for sloping the bottom at an outer zone and having a trough forming flange at the margin of the aperture opposite the slope, the marginal portion of said distributor being adjustable up and down relative to the upper conical surface of the distributor and overhanging and substantially parallel to the zone of the bottom of the recess next inward from the sloping outer zone; said marginal portion of the distributor being adjustable down into the trough for varying simultaneously and similarly the air gaps at both circumferences of said peripheral zone.

4. A fuel mixer and burner for heating furnace and the like, comprising a support adapted to be mounted in the fire box of the furnace to be served and having a depressed area forming a basin and an air inlet aperture therethrough; a fuel supply pipe extending up through said aperture; the fuel distributor at the upper end of said pipe being apertured in alignment therewith for discharge of fuel upwardly through said distributor, the support having another aperture and an air pipe connected therewith above the support and extending thereabove in the fire box chamber and reflexed therein for discharge downwardly toward the distributor, the first mentioned aperture in the support having a marginal upwardly trending flange forming an annular trough around said aperture, said distributor comprising a disc constituting the lower part thereof whose diameter is such that its circumferential margin overhangs said annular trough, said disc being mounted adjustably up and down for varying the air gap between the same and the edge of the trough.

5. A fuel mixer and burner for heating furnace and the like, comprising a support adapted to be mounted in the fire box of the furnace to be served, and having a depressed area forming a basin and an air inlet aperture therethrough; a fuel supply pipe extending up through said aperture; the fuel distributor at the upper end of said pipe being apertured in alignment therewith for discharge of fuel upwardly through said distributor, the support having another aperture and an air pipe connected therewith above the support extending thereabove in the fire box chamber and reflexed therein for discharge downwardly toward the distributor, the depression in the upper side of the support being substantially frusto-conical in form for sloping the bottom down inwardly at an outer zone, and an opposite trough-forming flange at the margin of the aperture, the distributor comprising at its

bottom part a disc mounted adjustably up and down and formed with an outer annular zone overhanging the zone of the bottom at the recess or basin next inwardly from the sloping outer zone and overhanging also the sloping marginal flange, said outer zone of the disc being substantially parallel to the zone at the bottom of the recess next inward from the sloping outer zone and having next inward from said parallel portion a zone sloping substantially parallel to the slope of said marginal flange; whereby said disc may be adjusted down to the trough for varying simultaneously and similarly the air gaps at both circumferences of the peripheral zone of said disc.

6. A fuel mixer and burner for heating furnace and the like comprising a support adapted to be mounted substantially horizontally in the fire box of the furnace to be served; said support having a central air aperture; a fuel supply pipe extending up through said aperture and oil distributor at the upper end of said fuel pipe apertured in alignment therewith for discharge of fuel from the fuel pipe above the distributor, said support having additional aperture and air duct connected therewith and extending above the support in the fire box chamber and reflexed for discharge downwardly over the distributor and the

fuel discharge pipe, and a choke damper mounted for up and down movement on the fuel supply pipe above the first mentioned air inlet aperture of the support and means for adjusting said damper to vary the air gap between the same and the margin of said aperture.

7. A fuel mixer and burner for a heating furnace and the like comprising a support adapted to be mounted in the fire box of the furnace to be served, and having a depressed area forming a basin, and an air inlet aperture therethrough; a fuel supply pipe extending up through said aperture, the fuel distributor at the upper end of said pipe apertured in alignment therewith for discharge of fuel upwardly and through said fuel distributor, said basin having an outer zone of its bottom sloping down inwardly; a choke damper mounted for up and down adjustment on the fuel supply pipe having its circumference overhanging said sloping zone of the basin bottom for limiting the air gap above the latter, and means for adjusting said damper up and down.

In testimony whereof, I have hereunto set my hand at Chicago, Illinois, this 23rd day of October, 1925.

HERMAN MILLER.
